HAND HELD, POWER OPERATED NIBBLER UNIT

Israel J. Yermish, Philadelphia, Pa., assignor to Fenway Machine Company, Inc., Philadelphia, Pa., a corporation of Pennsylvania

Application July 30, 1957, Serial No. 47,152

Term of patent 14 years

(Cl. D54—14)

Figure 1 is a perspective view of a hand held, power operated nibbler unit showing my new design;

Figure 2 is a top plan view thereof;

Figure 3 is a front elevational view thereof; and

Figure 4 is a partial side elevational view thereof, showing the head of the unit.

I claim:

The ornamental design for a hand held, power operated nibbler unit, substantially as shown.
